UNITED STATES PATENT OFFICE.

HENRY S. MONTGOMERY, OF TOPEKA, KANSAS.

DESIGN FOR A TIMEPIECE-DIAL.

55,523.

Specification for Design.

Patented June 22, 1920.

Application filed March 18, 1918. Serial No. 223,238. Term of patent 14 years.

To all whom it may concern:

Be it known that I, HENRY S. MONTGOMERY, a citizen of the United States, residing at Topeka, in the county of Shawnee and State of Kansas, have invented a new, original, and ornamental Design for a Timepiece-Dial, of which the following is a specification, reference being had to the accompanying drawings, forming part thereof.

The figure is a front elevation of a timepiece dial showing my new design.

I claim:—

The ornamental design for a timepiece dial as shown.

HENRY S. MONTGOMERY.

Witnesses:

PEGGY G. HAGAR,

R. A. MONTGOMERY.
